UNITED STATES PATENT OFFICE:

HENRY WRIGHT HALLEY, OF HUTCHINSON, KANSAS.

INSOLE.

1,236,427.

Specification of Letters Patent. Patented Aug. 14, 1917.

Application filed January 22, 1915. Serial No. 3,791.

To all whom it may concern:

Be it known that I, HENRY W. HALLEY, a citizen of the United States, residing at Hutchinson, in the county of Reno and State 5 of Kansas, have invented certain new and useful Improvements in Insoles, of which the following is a specification, reference being had therein to the accompanying drawing.

10 My invention relates to insoles for shoes and has for its principal object to distribute and hold antiseptic or other material in a shoe in such manner as to produce maximum effect with minimum waste. Ancillary objects will sufficiently appear in the description hereinafter.

In order to attain my object, I provide an insole with small wells or partial perforations distributed with approximate uniformity throughout its upper surface. These wells or perforations are in practice filled with the desired material. The nature of this material may be varied according to requirements without departing from the spirit 20 of the invention. Thus, an antiseptic powder may be distributed and held without waste in the little wells, or plain talcum, or soapstone powder, or grease for pedestrians, or other medicaments of various sorts, dry 25 or not, and it is to be particularly observed that since the wells are in the upper part of the insole and do not extend through the material, the medicament is retained where it is needed, next the foot, and does not under any conditions reach the structure of the 30 shoe sole. This is particularly desirable where a material is employed which might soften or rot the stitching. It is not unusual for those engaged in sports such as golf, or 35 in walking for considerable periods, to lubricate their stockings, at least on the soles, in order to prevent undue friction and heating with constant formation of blisters. Obviously, however, after the sole of a shoe has 40 been greased in this way and the grease rubbed in, it can only be used for purposes requiring grease, and the same may be said of medicaments of any kind. With my invention on the other hand, the sole may be 45 kept thoroughly lubricated by deposits of grease or medicament in the little wells, and if it be desired to use the shoe afterward with different stockings or for a different purpose, it is only necessary to remove the 50 insole which brings with it all of the grease,

powder, or whatnot which has been employed.

My invention is illustrated in the accompanying drawings in which—

Figure 1 is a plan view of an insole constructed according to my invention. 60

Fig. 2 is a longitudinal section on the line $x-x$ of Fig. 1.

Referring to the drawing, the insole 1 is provided with small wells or semi-perforations 2, which it will be observed are distributed with approximate uniformity throughout its surface. There are more of these perforations under the ball of the foot and directly under the heel than under the instep, partly due to the contour of the insole and partly to the fact that no pressure is exerted on the spring or arch portion of the sole. 70

In constructing this insole, the holes may 75 be pressed or drilled or otherwise produced in a solid body of material such as leather, or as indicated in Fig. 2, they may be punched through one component layer of the material, and not through the other. 80

In making a two-part insole, the parts may be punched either in two operations or in one, that is to say either with separate punches or a combination punch. In the latter case there will have to be a change in 85 the tool after the requisite number of perforated layers are produced, so that the balance of the layers will be turned out solid. These are then matched together in pairs, and cemented and stitched or otherwise secured together, so as to form a solid integral body with the wells or perforations extending only part way through it. 90

In practice, powder is placed in a shoe 95 containing this insole and the shoe shaken or moved about to distribute the powder over the insole and thereby fill all the wells. When this has been accomplished, the surplus powder may be removed, and in order that the wells may not again be emptied by 100 this process, it is well to introduce the powder by degrees so the shoe will not have to be inverted thereafter. The wells then retain the powder during wear, and the suction of the foot rising and falling in relation 105 to the insole will maintain a thin but constant layer of powder over the entire surface of the sole. When at rest, the vapor of the antiseptic employed will be distributed with equal uniformity and efficiency. 110

I have found that when my improved insole is used without antiseptic powder, it has certain beneficial properties one of which is that it appears to afford rest to the foot. This 5 may be due to some ventilating effect of the partial apertures, which permits ready distribution and evaporation of moisture and vapors. Another beneficial property is that the small wells with solid or hermetically 10 closed sides and bottoms create suction between the foot and the insole and afford a greater coefficient of friction or a greater resistance to longitudinal motion of the foot than an ordinary smooth polished insole. In 15 walking, with heeled shoes of ordinary construction, there is a tendency for the foot to be thrown forward in the shoe with the result that pressure is exerted not only laterally in a compressive manner upon the small 20 bones of the toes and the ball of the foot, but also rearwardly against the arch of the instep; and if such pressure is maintained, that is to say, if walking is persisted in with shoes that do not allow free movement of 25 the bony arch of the instep, there will be a tendency for this arch to break down, producing what is known as flat foot. This effect has been very noticeable in women's shoes of some types, such as are fitted with 30 high heels, also in men's shoes when the so-called "Cuban" heels or "Spanish" heels are worn. The effect is never absent from any shoes having heels, because each step forward in the rolling motion of walking, 35 brings a forward impulse to the foot swinging on the ball, while the shoe is held back by friction against the ground. It will be quite obvious that a smooth or polished insole, especially one which has been powdered, 40 lends itself freely to this forward tendency of the foot. With my insole, on the contrary, it tends to hold the foot back where it belongs, with the heel resting solidly over the heel of the shoe, the arch over the spring 45 or arch of the shoe, and the ball of the foot on the broad tread thereof. I do not broadly claim perforations for this purpose, as I am aware that completely perforated soles have 50 been used for different purposes, such as that of ventilation. I do claim, however, the use of partial perforations or wells in the insole

for the purposes stated, and I contemplate as part of my invention all modifications of the structure or method herein described which fall fairly within the scope of the 55 appended claims.

While I have mentioned leather as a material for my insole, it is to be understood that other materials may also be employed without departing from the purview of the 60 invention. Among the materials which would be suitable to meet general or special conditions I may mention indurated fiber, compressed paper or fabric, and combinations of materials, whether in separate layers, each of a single material, or in one composition unit. As a means for applying medicaments to the feet, my device may even be used without a shoe, being bound to the foot in any suitable manner, or it may be 65 provided with heel and toe straps or inclosures, and be used itself as a sandal or slipper.

Having thus described my invention what I claim and desire to secure by Letters Patent is:

1. An insole having a solid continuous body of substantially uniform thickness provided with a plurality of relatively small depressions or wells with solidly closed sides and bottoms, distributed over the bearing 80 surface upon which the user's foot will rest, and sufficiently tight and proof against leakage to create suction between the foot and the insole, to receive and retain medicaments when desired, and to prevent said medicaments when employed from passing through the insole.

2. An insole having a solid body provided with a plurality of relatively small depressions or wells in its upper side, with 90 solidly closed sides and bottoms, said wells being filled with antiseptic material.

3. An insole having a solid body provided with a plurality of depressions or wells in its upper side filled with antiseptic powder. 95

In testimony whereof I affix my signature in presence of two witnesses.

HENRY WRIGHT HALLEY.
